UNITED STATES PATENT OFFICE.

ORRELL ASHTON, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,032,356.

Specification of Letters Patent.

Patented July 9, 1912.

Original application filed September 11, 1911, Serial No. 648,635. Divided and this application filed March 27, 1912. Serial No. 686,485.

To all whom it may concern:

Be it known that I, ORRELL ASHTON, a citizen of the United States, residing at Swampscott, in the county of Essex and State of Massachusetts, have invented certain Improvements in Machines for Use in the Manufacture of Boots and Shoes, of which the following description, in connection with the accompanying drawings, is a specification, like reference characters on the drawings indicating like parts in the several figures.

This invention relates to machines for use in the manufacture of boots and shoes and particularly to shoe shaping machines. The invention is herein shown as adapted for use in connection with a machine of the type shown in British Patent No. 16,589/08, and this application is a division of application Serial No. 648,635, filed Sept. 11, 1911. This type of machine comprises a rotary beater which includes a very rapidly rotated carrier or hub having annular end disks, between which disks extend stems or rods arranged around the periphery of the carrier and supporting an annular series of beating elements which strike a very rapid succession of light blows. The beating elements are arranged to be held out radially from the carrier by centrifugal force in normal operative position while the beater is rotating, and to yield inwardly when they strike the work. Machines of this type are employed with great success in pounding up the overlasted marginal portions of shoe upper at the sides of the heel seat and, in some classes of work, along the sides of the shank portions and forepart of the shoe bottom.

The invention comprises the provision of new and improved work resting and guiding means especially adapted for use in a machine of the type aforesaid when, in a common use thereof, it is desired to present the heel seat of a shoe to the beater for treatment of one edge at a time. For sustaining one side of the heel portion of the shoe during treatment by the beater of the heel seat at the other side, a horizontal member is

provided. This member forms a rest about which the operator may rock the shoe longitudinally for presenting it to the beater for treatment. In order to compensate for the lift of the shoe as it is thus turned about the rest, the upper face of the rest is preferably curved so as to present a convexly rounded work resting surface. This provides that during the turning of the shoe the successive portions of the shoe presented to the beater will be in substantially the same horizontal plane and, therefore, in proper relation to the beater. Associated with the horizontal work resting member is a vertical abutment particularly adapted and arranged to prevent the beater from engaging and forcing outwardly toward the edge of the last bottom the upper on the lower side of the heel seat while the beater is forcing inwardly the upper on the upper side of the heel seat.

Before a lasted shoe comes to the beater, the upper on the heel seat of the shoe has been permanently fastened by fully driven tacks. The portions of the overlasted upper along the shank immediately in front of the heel seat are however held by temporary partially driven side lasting tacks which must not be disturbed in the heel seat beating operation. Furthermore, if the beater were to engage this portion of the shoe upper it would knock out of shape the insole lip to which the upper is later to be secured by the welt attaching machine. It is therefore important that the portions of the upper held by the rear side lasting tacks should be protected from the action of the beater. Accordingly the vertical rest or guide is also arranged to protect the shank region of the shoe bottom from being engaged by the beater. To this end, the upright guide is provided with vertical lateral edges adapted by engagement with the rear partially driven side lasting tacks to limit lengthwise movement of the shoe heelward and thus to restrict the action of the beater to the desired field of operation. Preferably, too, the upper corner portions

of the vertical guiding and resting member will each have a similar curvature to that of the upper face of the horizontal member so that, as the operator turns the 5 shoe, the lateral edge of the vertical guide will be in sliding contact with the rear side lasting tack, thus insuring that the vertical guide will all the time during the turning of the shoe protect those portions of the upper 10 which are held by the side lasting tacks from being disturbed by the beater.

In accordance with a further feature of the invention the upper surface or edge of the upright supporting member is preferably beveled so as to facilitate tipping the shoe transversely of its longitudinal axis for presenting the shoe to the beater at the desired angle and with the necessary pressure.

20 These and other features and advantages of the present invention, including certain details of construction and combinations of parts, will be fully set forth and explained in the following detailed description of so 25 much of a machine embodying a preferred form of the invention as is necessary for a complete understanding thereof, and will then be clearly defined in the appended claims.

30 Referring to the drawings: Figure 1 is an angular perspective in elevation of so much of the machine as is concerned with the present invention; Fig. 2 is a plan view partly in section showing a beating element in operative relation to an edge of the heel seat, 35 of a shoe; Fig. 3 is an end view in elevation, showing in detail the operative relation between the beater, the shoe resting and guiding means and the work; Fig. 4 is a front view in elevation showing in detail the relation of the shoe to the beater and the work resting and guiding means in the first position of the shoe; Fig. 5 is a view similar to Fig. 4, showing the last or extreme 40 position of the shoe, with relation to the beater and the shoe resting and guiding means.

Bearings 2 on the frame of the machine support a shaft 4, upon which is mounted a 50 hub or carrier having end disks or flanges 6. The end disks 6 are connected by rods or stems 8 which support an annular series of beating elements 10 confined at their ends by collars 12.

55 As shown in Fig. 1, the above described beater may advantageously be employed in conjunction with a plate 14 which extends into close proximity to the outer-most position of the beating members, and is adapted 60 to engage the side of the shoe. This plate 14 for resting the shoe coöperates with the beating members in shaping the side of the shoe at and adjacent to the edge of the last

by reason of the pressure of the shoe against it. The said plate may be stationary or, 65 conveniently, to facilitate its coöperative action, it may be actuated by suitable means to beat or rub the upper.

For beating the sides and the bottom of the heel portion of the shoe and also the 70 sides of the forepart of the shoe bottom, the shoe may be rested on a horizontal member 16, as illustrated in Figs. 4 and 5. In the common use of the machine for heel seat beating, the said member 16 will thus serve 75 as a rest for one side of the heel portion of the shoe at a time for presenting the shoe to the beater for treatment of the heel seat at the other side, as clearly shown in Fig. 3. Preferably, and as shown, the upper face of the member 16 is convexly rounded to facilitate turning the shoe from the first position shown in Fig. 4 to the extreme position shown in Fig. 5, and to insure that during this turning the successive 80 portions presented to the beater will be in the same horizontal plane, thus compensating for the lift of the shoe.

The member 16 has associated with it a 90 vertical abutment or guide which consists of a relatively thin plate 18, having a horizontal extension 20 supported upon a flat part 22, fixed to an upright post 24 which is adjustably secured in a bracket on the machine frame by a set screw. The horizontal rest 16 caps the extension 20 of the vertical guide 18 and a set screw 23 passing through a hole in the part 22 and through a somewhat elongated transverse slot 27 in the extension 20, has screw threaded engagement with the rest 16, thereby binding the said parts together. By reason of the elongated transverse slot in the extension 20, the vertical guide 18 can, if desired, be 95 adjusted toward or from the beater.

The end portions of the guide 18 form at 100 each lateral side of the rest 16 vertical stops 26 which are intended and arranged, as shown in Figs. 4 and 5, to engage the heel side of the rear partially driven side lasting tack 25 on the side of the shoe supported by the rest 16. These stops during the action of the beater upon the heel seat at the other side, serve to restrict lengthwise movement of the shoe heelward, limiting the field 110 of action of the beater so as to prevent engagement of the beater with the portion of overlaid upper held by the side lasting tacks. The member 18 also constitutes a 115 guard to prevent the beater from engaging and forcing toward the edge of the last bottom the upper on the lower side of the heel seat while the beater is forcing inwardly the upper on the upper side of the heel seat. Moreover, if it is desired to treat the shank 120 region of the shoe, the vertical member in

125

stead of engaging a rear side lasting tack may be interposed between the beater and the side lasting tacks on the lower side of the shank, and by such interposition prevent these tacks from being disturbed during treatment of the shank at the upper side. Preferably, the upper corner portions of the vertical rest 18 are rounded similarly (Fig. 1) to the upper face of the member 16. As a result, for manipulating the shoe from the first position shown in Fig. 4 to the last or extreme position shown in Fig. 5, the shoe may be rocked about the rest 16 without disturbing the guiding engagement of the member 18 with the rear side lasting tack 25 which will slide along the edge of the member 18 as the shoe is turned.

In order to facilitate tipping the shoe transversely of its longitudinal axis, causing the side of the heel seat to be treated to bear against the beater with the required pressure and at the desired angle, the upper and end edge portions of the vertical member 18 may be beveled as illustrated in Fig. 1. Although, for convenience, the above described work resting and guiding means are herein shown in connection with the machine shown and described in applicant's co-pending application Serial No. 648,635, of which as above stated this application is a division, the said machine *per se* is not claimed herein, the novel features thereof being claimed in the said co-pending application.

Having thus fully described one illustrative embodiment of this invention, what I claim as new and desire to secure by Letters Patent of the United States is:

1. In a machine of the class described, a beater, a horizontal work resting member, and an adjacent vertical abutment between the horizontal member and the beater, arranged to serve as a guard to prevent the beater from engaging and forcing toward the edge of the last bottom the upper on the lower side of the heel seat while the beater is forcing inwardly the upper on the upper side of the heel seat.

2. In a machine of the class described, a beater, a horizontal rest for engagement with one side of the heel portion of a shoe and a vertical abutment adapted to engage the bottom of the shoe at one edge and mounted for adjustment in a substantially horizontal plane transversely of the longitudinal axis of the shoe toward and from the beater.

3. In a machine of the class described, a beater to which the heel portion of a shoe is to be presented for treatment of one side at a time, and means arranged for lateral engagement with the rear side of a projection

provided on the shoe bottom to facilitate positioning the shoe while a side of the heel seat is being presented to the beater.

4. In a machine of the class described, a beater, a rest for engagement with one side of the heel portion of the shoe while the heel seat at the other side is being beaten, and means arranged at each lateral side of the rest to engage the rear side lasting tacks of a lasted shoe to guide the operator in presenting the shoe to the beater for treatment successively of the opposite sides of the heel seat.

5. In a machine of the class described, a beater, a rest for engagement with one side of the heel portion of the shoe while the heel seat at the other side is being beaten, and vertical stops at each lateral side of said rest in position to engage the rear partially driven side lasting tacks of a lasted shoe and guide the operator in so presenting the shoe to the beater that the portions of the upper, held by the side lasting tacks, will be prevented from engagement with the beater.

6. In a machine of the class described, a beater, a rest for engagement with one side of the heel portion of a shoe while the heel seat at the other side is being beaten, and means arranged at each lateral side of the rest to engage the rear side lasting tacks of a lasted shoe to guide the operator in presenting the shoe to the beater, said rest having its work resting face convexly curved and said abutment having rounded corners.

7. In a machine of the class described, a beater, a horizontal rest for engagement with one side of the heel portion of a shoe and a vertical guide adjacent to the said rest adapted to engage the heel seat of a shoe at one side, the said guide having its upper edge beveled to facilitate tipping the shoe transversely of its longitudinal axis about the said upper edge of the guide for presenting the other side of the heel seat to the action of the beater.

8. In a machine of the class described, a beater, a rest for engagement with one side of the heel portion of a shoe while the heel seat at the other side is being beaten, and a vertical stop at one lateral side of the said rest to guide the operator in presenting the shoe to the beater.

9. In a machine of the class described, a beater to which the bottom of a shoe is to be presented for treatment of one side at a time and a vertical abutment arranged to prevent the beater from engaging the upper on one side of the shoe bottom while the beater is treating the upper on the other side of the shoe bottom.

10. A machine of the class described having a beater, a horizontal work resting mem-

ber for engagement with one side of the heel portion of the shoe while the shoe bottom at the other side is being beaten and having a convexly rounded work resting face, and an adjacent vertical abutment to serve as a guard to prevent the beater from engaging the upper on one side of the shoe bottom while the beater is treating the upper on the other side, said abutment having its upper

edge beveled and having rounded corners 10 for the purpose described.

In testimony whereof I have signed my name to this specification in the presence of two subscribing witnesses.

ORRELL ASHTON.
